Primary Examiner—Theodore M. Shooman*Assistant Examiner*—C. Tuttle*Attorney, Agent, or Firm*—Klarquist Sparkman Campbell Leigh & Whinston[57] **CLAIM**

The ornamental design for a combined travel hairdryer and iron, as shown and described.

DESCRIPTION

FIG. 1 is a top plan view of a combined travel hairdryer and iron in accordance with the present invention;

FIG. 2 is a left side elevational view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is an exploded perspective view thereof;

FIG. 8 is a right side elevational view of the iron portion with the dryer portion removed for clarity of illustration;

FIG. 9 is a left side elevational view of the dryer portion with the handle retracted, and with the iron portion removed for clarity of illustration;

FIG. 10 is a rear elevational view shown with the handle in an extended position;

FIG. 11 is a front elevational view thereof;

FIG. 12 is a right side elevational view thereof; and,

FIG. 13 is a bottom plan view thereof.
